[57] CLAIM

The ornamental design for a "bird feeder", substantially
as shown and described.

DESCRIPTION

FIG. 1 is a perspective view taken from the top, front
and left side of a bird feeder showing my new design;
FIG. 2 is a top plan view thereof;
FIG. 3 is a rear elevational view thereof;
FIG. 4 is a right side elevational view thereof; and
FIG. 5 is a bottom plan view thereof.
